UNITED STATES PATENT OFFICE.

WILLIAM S. HAMM, OF CHICAGO, ILLINOIS, ASSIGNOR TO THE ADAMS & WESTLAKE COMPANY, OF ILLINOIS.

DESIGN FOR A BICYCLE-LAMP.

SPECIFICATION forming part of Design No. 26,794, dated March 23, 1897.

Application filed February 5, 1897. Serial No. 622,220. Term of patent 14 years.

To all whom it may concern:

Be it known that I, WILLIAM S. HAMM, a citizen of the United States, residing in the city of Chicago, in the county of Cook and State of Illinois, have invented and produced a new and original Design for Bicycle-Lamps, of which the following is a specification, reference being had to the accompanying drawings, forming a part thereof.

10 Figure 1 is a perspective view of a bicycle-lamp constituting my design. Fig. 2 is a similar perspective view from a different point of observation.

15 A is the main body of the lamp, which is substantially of spherical or globular formation, as shown.

20 B represents the oil-reservoir, which constitutes the base of the lamp. The oil-reservoir B is of a diameter only slightly less than that of the main body A and has a curved surface *a* and flat surfaces *b*. Between the oil-reservoir and the main body is a straight or cylindrical portion or neck *c*.

25 C is the dome, the distinguishing feature of which is its height as compared with the height of the remainder of the lamp. The dome is connected to the main body of the lamp by a flange, in which are the slits *d*. Above these slits the base portion of the dome is beaded,

as at *e*, it then being given a dome formation, 30 as at *f*, after which it rises into a cylinder *g*, divided by a bead *g'*, the cylinder being of smaller diameter than the dome-shaped lower portion and surmounted by an enlarged cap portion *h*, in which are the slits *i*, the cap being continued in the shape of the frustum of a cone *k* and topped by the plate *l*. 35

The dome C as an entirety is of substantially less diameter than the main body A of the lamp. 40

D is the front lens, supported by an outwardly-flaring framing E, projecting from the main body A.

F F are the side lights or jewels, which are circular and convex and inclosed in frames 45 G, extending from the main body A. In the rear of the main body A is a circular cavity or recess G', surrounded by a raised edge *n*.

What I claim is—

The design for a bicycle-lamp, substantially 50 as herein shown and described.

In testimony whereof I hereunto set my hand and seal, this 13th day of January, 1897, at the said city of Chicago.

WILLIAM S. HAMM. [L. S.]
